UNITED STATES PATENT OFFICE.

JOHN ARTHUR MOREN, OF WEBSTER, WISCONSIN.

TELEPHONE ATTACHMENT FOR MOTOR VEHICLES.

1,416,116.

Specification of Letters Patent. Patented May 16, 1922.

Application filed December 27, 1920. Serial No. 433,201.

To all whom it may concern:

Be it known that I, JOHN A. MOREN, a citizen of the United States, residing at Webster, in the county of Burnett and State of Wisconsin, have invented certain new and useful Improvements in Telephone Attachments for Motor Vehicles, of which the following is a specification.

This invention relates to a telephone device 10 for use in connection with motor vehicles.

One object of the present invention is to provide an attachment which is of such nature that it affords facilities for telephoning at any point along a highway during 15 travel by motor.

One of the special features of the invention resides in the provision of an outfit of this character which is so made that it is capable of being stored in an exceedingly 20 small space and yet is adapted for tapping into the telephone lines carried on the poles alongside of the highway.

The invention also includes means whereby 25 one of the terminals of the telephone outfit may be easily raised to the desired height for attachment of said terminal to a wire carried by telephone poles.

The invention furthermore provides means whereby 30 a telephone lineman traveling along the highway may carry with him a compact outfit whereby he will be enabled, at any point, to get in touch with his home office by simply attaching the device to one of the telephone lines.

35 In the drawings—

Figure 1 is a perspective view showing the invention in use;

Figure 2 is a perspective view showing the operator of a motor vehicle in the act 40 of connecting up the invention for use;

Figure 3 is a detail view showing the means for connecting the device into the telephone line;

Figure 4 is a detailed perspective view of 45 the terminal attaching means.

The invention, as herein shown for the purpose of disclosing the same, comprises a telephone set 1 having the connecting leads 2 and 3, the former of which is adapted to be connected to the ground of the circuit, such ground being effected by the use of a copper peg 4 with which the lead 2 is connected and which peg is firmly driven into the ground. It is also obvious that a good 50 ground may be made by connecting the lead

wire 2 with the radiator or any other metal portion of the vehicle and then subsequently connecting the vehicle with the ground in any suitable manner.

The lead wire 3 is connected at its end 5 60 with an eye 6 of a contact strip 7 having a hook 8 at its other end, said contact strip 7 being securely welded to a tubular ferrule 9 threaded as indicated at 10 at one end, said end being opposite the hook 8 and carrying a 65 funnel 11 for purposes to be hereinafter set forth.

A sectional pole 12 joined together as shown at 13 with threaded ferrules 14 is provided and has its uppermost end adapted 70 to engage the threads 10 of the tubular ferrule 9.

In using the device the operator of the vehicle first grounds the telephone set 1 by driving the peg 4 into the ground, or otherwise. Next, the jointed sections 12 of the 75 pole are secured together in the manner indicated at 13 and the upper end of the pole is screwed into the threads 10 of the ferrule 9, said threads fitting relatively loose so that 80 after the ferrule 9 has been hung upon the wire by the hook 8 the pole may be detached.

After the operator has finished using the device and desires to remove the ferrule 9 the end of the pole is again screwed into the 85 threads 10, being guided into the same by the funnel 11 which provides a large opening for initially receiving the end of the pole and directing it into proper place.

The ferrule 9 constitutes a weight for holding 90 the hook 8 in electrical contact with the wire and consequently is made of relatively heavy material while the contact strip 7 is preferably made of copper to provide good conductivity. The conductivity of the ferrule 9 may be nil. 95

I claim:

In combination with a portable telephone set for tapping into a telephone line, lead wires one constituting a ground wire and 100 the other a line connecting wire, a tube provided at one end with a pole centering funnel, and a longitudinally extending contact strip secured to the tube at one side thereof, said strip being provided at one end with an 105 eye accommodating the line connecting wire and at its opposite end with a hook to engage over a line wire.

In testimony whereof I affix my signature.

JOHN ARTHUR MOREN. [L.S.]
